DOOR LOCK

Avery G. Johns, Des Moines, Iowa

Application August 27, 1956, Serial No. 606,237

4 Claims. (Cl. 70—451)

This invention relates to a door lock and more particularly to one that has a common manually actuated locking mechanism selectively operable from each side of the door.

Door locks are very old. They usually take the form of a key actuated bolt, with a keyhole at both sides of the door. To actuate the locking means a key is inserted in the keyhole at one side of the door either to lock or unlock the door. Then the key is removed, the door used, and then to lock or unlock the door, the key must be inserted in the other keyhole and actuated. In case of poor lighting at either side of the door, this insertion of the key is most difficult. Also time is lost in removing the key from one keyhole and then inserting it in the keyhole on the other side of the door.

Therefore, one of the principal objects of my invention is to provide a door lock that eliminates the removal of the key means from one side of the door to the other side of the door.

More specifically, the object of this invention is to provide a door lock that may be rotated to bring the key means to either side of the door without necessitating the removal of the key.

A further object of this invention is to provide a door lock that is capable of being turned to a position where there is no keyhole at one selected side of the door.

Still further objects of my invention are to provide a door lock that is economical in manufacture, durable in use, and refined in appearance.

These and other objects will be apparent to those skilled in the art.

My invention consists in the construction, arrangements and combination, of the various parts of the device, whereby the objects contemplated are attained as hereinafter more fully set forth, specifically pointed out in my claims, and illustrated in the accompanying drawings, in which:

Fig. 1 is a perspective view of my lock installed in a door,

Fig. 2 is a vertical sectional view of the lock with the keyhole on one side only, and is taken on line 2—2 of Fig. 4,

Fig. 3 is a horizontal view of the device taken from a line 3—3 of Fig. 4, and

Fig. 4 is a vertical sectional view of the lock taken from a line corresponding to line 4—4 of Fig. 3, and more fully illustrates its construction.

In these drawings I have used the numeral 10 to designate a door jamb or casing frame in a building. The numeral 11 designates a door hinged in the opening of the casing frame. The numeral 12 designates a horizontal well in the casing frame for receiving a sliding bolt lock. In the door 11 and adjacent the well 12 (when the door is in closed position) I cut a notch 13. Into this notch I secure a bearing frame 14 having a horizontal well 15 in its back for receiving a sliding bolt lock.

2

When the door is closed, the two wells 12 and 15 are opposed to each other and extend in diametrically opposite directions.

The numeral 16 designates the lock frame housing having a bearing lug 17 on its top rotatably mounted in the bearing frame, and a bearing lug 18 on its bottom also rotatably mounted in the bearing frame. These two lugs 17 and 18 extend vertically, are opposed relative to each other, and horizontally rotatably secure the lock housing frame in the door, as shown in Fig. 4. While I show lugs 17 and 18, any other suitable means or arrangement may be used to rotatably mount the housing frame in or to the door. Slidably mounted in the housing frame are two opposed locking bolt shafts 19 and 20. These two bolts 19 and 20 extend in opposite directions and are adapted to selectively engage the wells 12 and 15 respectively. Any suitable throw means may be used to actuate these bolts 19 and 20. In the drawings I show a cylinder lock 21 mounted in the housing 16 and the rotatable plug of the cylinder lock is operatively connected to the rear ends of the bolts 19 and 20, as shown in Fig. 4. I lay no claim to the specific mechanism inside the housing inasmuch as all such lock mechanisms are old. Such mechanisms are manually operated by a handle knob key or like. When the plug of the cylinder lock 21 is rotated in one direction the two bolts will move away from each other and into the wells 12 and 15, and when rotated in the opposite direction the bolts 19 and 20 will move toward each other and from and out of the wells 12 and 15.

In the drawings I show a detachable key 22 to facilitate the rotation of the plug of the cylinder lock 21. In Fig. 1 and Fig. 2 I show only one keyhole plate 23 on one side only of the housing 16 and having a keyhole 24 for receiving the key 22. The numeral 25 designates a plate on the other side of the housing 16.

The operation of the device is as follows:

In Fig. 1 the door is closed and locked. To pass through the door and lock it from the outside, a key is placed in the keyhole 24 and rotated to withdraw the two bolts 19 and 20, one then passes through the door, rotating the housing 16 to bring the key to the outside of the door. By again turning the key, the bolts will be extended to engage the wells 12 and 15. After locking the door, the key is removed. Thus, to unlock the door from one side, and then lock it from the other side, the key is only inserted and withdrawn once. The bolts 19 and 20, however, will be reversed, i.e., the bolt that was penetrating the well 12 will lastly penetrate the well 15. To unlock the door from the outside, the same procedure is followed. The key is inserted and the door unlocked and then the housing 16 is horizontally rotated to bring the key to the inside of the door for locking the door from the inside. With only one keyhole, as shown in Fig. 2, once one has locked the door from the inside, there is no key hole on the outside of the door and therefore my device provides almost a burglar proof lock. In some instances, however, it will be desirable to have a keyhole at each side of the housing, as shown in Fig. 3. In some installations only one bolt lock will be used. However, by using both bolts 19 and 20, the lock housing is held from rotation relative to the door by one of the bolts detachably engaging the well 15.

Some changes may be made in the construction and arrangement of my door lock without departing from the real spirit and purpose of my invention, and it is my intention to cover by my claims, any modified forms of structure or use of mechanical equivalents which may be reasonably included within their scope.

I claim:

1. In combination, a door frame having a bolt lock receiving well, a door hinged in said door frame having a bolt lock receiving well and a notch adjacent thereto, a lock housing having at least two opposite portions of its periphery arcuate and rotatably mounted in the notch in said door, two opposed slideable bolt lock shafts in said housing, a means connecting said two bolt lock shafts whereby when one shaft is slid outwardly in one direction the other shaft will be moved outwardly and when one of said shafts is moved inwardly in one direction the other shaft will be moved inwardly, and a means at one side of said housing operatively connected to at least one of said two shafts for effecting the sliding moving of both of said shafts; said lock housing being mounted to rotate on an axis lying in a plane perpendicular to a plane parallel to the path of movement of the said slideable bolt lock shafts whereby the said lock housing is capable of rotation when the slideable bolt lock shafts are retracted from the bolt lock receiving wells in said door frame and said door; said lock housing capable of being rotated to selectively bring either of said bolt lock shafts into alignment with the well of said door frame or the well in said door.

2. In combination, a door frame having a bolt lock receiving well, a door hinged in said door frame having a bolt lock receiving well and a notch adjacent thereto, a lock housing rotatably mounted in the notch in said door, two opposed slideable bolt lock shafts in said housing, a means connecting said two bolt lock shafts whereby when one shaft is slid outwardly in one direction the other shaft will be moved outwardly and when one of said shafts is moved inwardly in one direction the other shaft will be moved inwardly, and a means at one side of said housing operatively connected to at least one of said two shafts for effecting the sliding moving of both of said shafts; said lock housing being mounted to rotate on an axis lying in a plane perpendicular to a plane parallel to the path of movement of the said slideable bolt lock shafts whereby the said lock housing is capable of rotation when the slideable bolt lock shafts are retracted from the bolt lock receiving wells in said door frame and said door; said lock housing capable of being rotated to selectively bring either of said bolt lock shafts into alignment with the well of said door frame or the well in said door.

3. In combination, a door frame having a bolt lock receiving well, a door hinged in said door frame having

a bolt lock receiving well, a lock housing rotatably mounted in said door, two opposed slideable bolt lock shafts in said housing, a means connecting said two bolt lock shafts whereby when one shaft is slid outwardly in one direction the other shaft will be moved inwardly and when one of said shafts is moved inwardly in one direction the other shaft will be moved outwardly, and a key actuated means at one side of said housing operatively connected to at least one of said two shafts for effecting the sliding moving of both of said shafts; said lock housing being mounted to rotate on an axis lying in a plane perpendicular to a plane parallel to the path of movement of the said slideable bolt lock shafts whereby the said lock housing is capable of rotation when the slideable bolt lock shafts are retracted from the bolt lock receiving wells in said door frame and said door; said lock housing capable of being rotated to selectively bring either of said bolt lock shafts into alignment with the well of said door frame or the well in said door.

4. In combination, a door frame having a bolt lock receiving well, a door hinged in said door frame, a lock frame rotatably mounted in said door, a slideable bolt lock shaft means in said lock frame having two opposed end portions capable of being selectively moved to bring either said end portions into said well, and a means on one side of said lock frame for effecting the sliding of said bolt lock shaft means; said lock frame being mounted to rotate on an axis lying in a plane perpendicular to a plane parallel to the path of movement of said slideable bolt lock shaft means whereby the said lock frame is capable of rotation when the slideable bolt lock shaft is retracted from the bolt lock receiving well in said door frame; said lock frame capable of being rotated to selectively bring either end of said bolt lock shaft means into alignment with the well of said door frame.
